The portion of the term of the patent subsequent to
Mar. 1, 1983, has been disclaimed
10 Claims. (Cl. 206—19)

ABSTRACT OF THE DISCLOSURE

A distributor for an internal combustion engine in which an interrupter turnable carried in the housing of the distributor is connected by a plug and socket type connection to a capacitor located outside of the housing and carried by a bracket fixed to the latter, and wherein one part of said plug and socket type connector extends through an opening in the housing and is removably carried by the aforementioned bracket.

The present invention relates to distributors for internal combustion engines.

Distributors of this type normally include a distributor housing in which an interruptor means is mounted for turning movement. In addition the distributor assembly includes an ignition capacitor connected in parallel with the electrical connection of the interruptor means to a source of primary current. It is conventional to mount the capacitor at the exterior of the distributor housing so that in this way it is possible to maintain the distributor housing at a minimum diameter far smaller than would be required if the distributor housing itself housed the capacitor.

In an arrangement of the above type wherein the capacitor is located at the exterior of the distributor housing considerable problems are created of conveniently connecting the interruptor in the interior of the distributor housing to the source of the primary current as well as of providing a parallel electrical connection between the interruptor and the capacitor which is at the exterior of the distributor housing.

Another problem inherent with distributor arrangements of the aforementioned kind is that when the capacitor is mounted on the housing by means of a bracket, the connection between the bracket and the housing may become loose due to the continued vibrations the distributor housing carried by the internal combustion engine is subjected during the running of the engine. This loosening of the bracket may lead to a tilting of the same and thereby to loosening of the contact establishing an electrical connection between the source of primary current and the interruptor which will detrimentally affect the proper functioning of the distributor.

It is accordingly an object of the present invention to provide for an inexpensive simple structure in a distributor for an internal combustion engine of the aforementioned kind which avoids the difficulties and problems mentioned above.

It is a further object of the present invention to provide an inexpensive and simple structure for establishing electrical connections between the interruptor and the capacitor where the latter is at the exterior of the distributor housing, as well as between the interruptor and the source of primary current.

It is an additional object of the present invention to provide a construction of the above type where the elec-

2

trical connections are arranged in such a manner to simplify assembly of the various components.

It is also an object of the present invention to provide a structure of the above type in which the electrical connector means are constructed and cooperate with the bracket which carries the capacitor in such a manner to prevent tilting of the bracket relative to the distributor housing even if the means for holding the bracket on the housing should become loosened.

With these objects in view, the distributor according to the present invention mainly comprises a distributor housing formed with an opening, interruptor means turnably carried by the housing, a plug and socket type connection means having at least two separable parts, one of which extends with a portion thereof through the opening to the exterior of the housing, first flexible conductor means inside the housing and connected at one end thereof to the interruptor means and at the other end thereof to the other part of the plug and socket type connector means, a capacitor located outside the housing, a bracket fixed to the housing at the exterior thereof carrying the capacitor, in which the portion of the one part of the connector means is constructed and arranged to engage the bracket so that said one part is removably carried by the bracket, and at least one flexible branch conductor means connected at one end thereof to the one part of the connector means and at the other end thereof to the capacitor.

Preferably, the distributor includes also a second flexible branch conductor means connected at one end thereof to the one part of the connector means and adapted to be connected at the other end thereof to a source of primary current. The one of the connector means preferably comprises an insulating body and a metal bar carried by the insulating body and having at least one free end in the form of a prong projecting beyond the body into the interior of the housing and the other part of the connector means is in the form of a socket removably engaging the prong to be mechanically and electrically connected thereto. The insulating body has preferably an inner portion extending through the opening in the housing and having a cross section substantially equal to that of the opening, and an outer portion located at the exterior of the housing which is formed with a pair of substantially parallel grooves respectively extending from opposite faces of the outer portion of the body into the latter, and the bracket has preferably a projection formed with a cutout open at one end in which the outer portion of the body is located with portions of the projection of the bracket to opposite sides of the cutout respectively located in the grooves.

In this way the bracket which carries the capacitor at the exterior of the housing is secured by the one part of the connector means against tilting and twisting even if the means which fasten the bracket to the housing should become loosened due to the vibrations the housing and bracket are subjected to.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings, in which:

FIG. 1 is a partially sectioned side view of the distributor arrangement according to the present invention; and

FIG. 2 is a partial perspective view of an arrangement differing slightly from that shown in FIG. 1.

Referring now to the drawings, and more specifically to FIG. 1 of the same, it will be seen that the distributor

according to the present invention mainly comprises a distributor housing 10 in which an interruptor means 17 is turnably mounted. The housing is formed with an opening therethrough and a plug and socket type connection means 11 is provided which has at least two separable parts, one of which extends with a portion thereof through the opening in the housing to the exterior thereof. In the embodiment shown in FIG. 1 the connector means 11 actually has three separable parts and the part extending through the opening of the housing includes an insulating body 12 which carries a metal bar 13 extending through the insulating body 12 and having two free end portions in the form of prongs 14 and 14' projecting inclined to the remainder of the bar 13 beyond opposite ends of the body 12. The other two separable parts of the three part plug and socket type connector means, in the embodiment shown in FIG. 1, comprises sockets 15 and 15' adapted to removably engage the prongs 14 and 14', respectively, to be mechanically and electrically connected thereto. A flexible conductor 16 connects the socket 15 with the interruptor means 17, whereas a flexible branch to conductor 18 is connected to the socket 15' at one end, whereas the other end thereof is adapted to be connected to the primary winding of an ignition coil. The distributor includes further a capacitor 19 which is fastened, for instance by spot welding, to a bracket 20 which in turn is fastened by a screw 21 to the outer surface of the housing 10. The capacitor 19 is connected in parallel to the interruptor 17 by means of a flexible branch conductor 23 the end 22 of which is connected, for instance by soldering, to the metal bar 13 of the connector 11.

While in the embodiment shown in FIG. 1 the connector means 11 has three separable parts, in the embodiment shown in FIG. 2 the part of the connector means 11' which is adapted to extend through the opening in the housing, not shown in FIG. 2, has a metal bar 13' which has only one free end 24 in the form of a prong projecting beyond one end of the insulating body 12 and adapted to be connected to the socket 15 at the end of the flexible conductor 16, while the flexible branch conductor 18' as well as the branch conductor 23 are fixedly connected, for instance by soldering, to the other end of the bar 13' and the insulating body 12 surrounds the ends of the flexible conductors 18' and 23 which are affixed to the bar 13'. In both arrangements the insulating body 12 insulates the metal bar 13, or 13' from the housing 10 and in the arrangement shown in FIG. 2 the insulating body protects also the ends of the flexible conductors 18' and 23 from damage or dirt.

In both embodiments, and best shown in FIG. 2, the bracket 20 is provided with an upwardly extending projection 25 formed with a rectangular cutout 26 open at the top and the insulating body 12 has an inner portion of a cross section substantially equal to that of the opening formed in the housing and an outer portion formed with a pair of substantially parallel grooves 27 which respectively extend from opposite faces of the outer portion of the body 12 into the latter. As is evident from FIG. 2, the portion of the insulating body 12 between the grooves 27 may be inserted into the cutout 26 so that the portions of the projection 25 on opposite sides of the cutout 26 are respectively located in the grooves 27 with the side faces of the cutout snugly engaging the bottom faces of the grooves 27, respectively. In the assembled position as shown in FIG. 1, the bracket 20 of the capacitor 19 is thereby secured against tilting or twisting by engagement with the insulating body 12 of the connector means 11 even though the bracket 20 is only secured by a single screw 21 to the housing 10. At the same time, the bracket 20 secures also the insulating body 12 of the connector means 11 against turning or axial displacement. In addition the capacitor 19, the bracket 20 and the insulating body 12 with its metal bars 13 or 13' form together a unit which can be easily removed by simply unscrewing the single screw 21. 75

This arrangement thereby greatly simplifies assembly or disassembly of the distributor.

It will be understood that each of the elements described above, or two or more together, may also find a useful application in other types of a distributor for an internal combustion engine differing from the types described above.

While the invention has been illustrated and described as embodied in a distributor for an internal combustion engine, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be secured by Letters Patent is:

- 25 1. In a distributor for an internal combustion engine, in combination, a distributor housing formed with an opening; interrupter means turnably carried by said housing; a plug and socket type connector means having at least two separable parts, one of which extends with a portion thereof through said opening to the exterior of said housing; first flexible conductor means inside said housing and connected at one end thereof to said interrupter means and at the other end thereof to the other part of said plug and socket type connector means; a capacitor located outside said housing; a bracket fastened to said housing at the exterior thereof and carrying said capacitor, said portion of said one part of said connector means being constructed and arranged to engage said bracket so as to be removably carried thereby; and at least one flexible branch conductor means connected at one end thereof to said one part of said connector means and at the other end thereof to said capacitor.
- 30 2. In a distributor as set forth in claim 1, and including a second flexible branch conductor means connected at one end thereof to said one part of said connector means and adapted to be connected at the other end thereof to the primary winding of an ignition coil.
- 35 3. In a distributor as set forth in claim 1, wherein said one part of said connector means comprises an insulating body and a metal bar carried by said body and having at least one free end in form of a prong projecting beyond said body into the interior of said housing, said other part of said connector means being in the form of a socket removably engaging said prong to be mechanically and electrically connected thereto.
- 40 4. In a distributor as set forth in claim 1, wherein said bracket is formed with a cutout having an open end, and wherein said portion of said one part of said connector means extends through said cutout of said bracket and is constructed to snugly engage said bracket at portions thereof to opposite sides of said cutout.
- 45 5. In a distributor as set forth in claim 3, wherein said insulating body has an inner portion extending through said opening and having a cross section substantially equal to that of said opening, said insulating body having an outer portion located at the exterior of said housing and being formed with a pair of substantially parallel grooves respectively extending from opposite faces of said outer portion of said body into the latter, and wherein said bracket has a projection formed with a cutout open at one end, said outer portion of said body extending through said cutout with portions of said projection to opposite sides of said cutout respectively located in said grooves.

6. In a distributor as set forth in claim 3, wherein said one end of said one flexible branch conductor means is fixed to said bar and said insulating body surrounding said one end of said one flexible branch conductor means.

7. In a distributor as set forth in claim 3, and including a second flexible branch conductor means, said one end of said one flexible branch conductor means and one end of said second flexible branch conductor means being fixedly connected to said bar and said insulating body surrounding said one end of said one and said second flexible branch conductor means, the other end of said second flexible branch conductor means being adapted to be connected to the primary winding of an ignition coil.

8. In a distributor as set forth in claim 1, wherein said plug and socket type connector means includes three separable parts, one of which extends with a portion thereof through said opening to the exterior of said housing, wherein said first flexible conductor means is connected at the other end thereof to a second part of said three separated parts of said connector means, and including a second flexible branch conductor means connected at one end thereof to the third part of said connector means and adapted to be connected at the other end thereof to the primary winding of an ignition coil.

10
15

20
25

9. In a distributor as set forth in claim 8, wherein said one part of said three part connector means comprises an insulating body and a metal bar carried by said body and having a pair of opposite free ends each in form of a prong and respectively projecting beyond opposite ends of said body, said second and third parts of said connector means being in form of sockets respectively removably engaging said prongs to being mechanically and electrically connected thereto.

10. In a distributor as set forth in claim 1, wherein said bracket is connected by a single fastening means to said distributor housing and wherein said portion of said one part of said connector is constructed and arranged to engage said bracket to prevent turning of the latter about the axis of said single fastening means.
